POPCORN DISPENSING DEVICE

Russell B. Hills and Herman E. Pleasant, Grand
Rapids, Mich.; said Pleasant assignor to said
Hills

Application November 30, 1938, Serial No. 243,168

14 Claims. (Cl. 221—144)

This invention relates in general to dispensing machines but has its particular adaptation to dispensing popcorn, and due to the peculiar nature of the popcorn itself the machine must be especially designed for this purpose.

In view of the fact that the nature of the popcorn does not permit it to be dispensed by the use of ordinary mechanism embodied in machines of this nature, it has become necessary to construct and embody certain elements not heretofore employed in vending machines. It has been determined that the usual flat horizontal rotatable disc used in dispensing machines will not operate satisfactorily to dispense popcorn because of the fact that the popcorn has a tendency to bridge itself over the opening through which it is to be dispensed, and to obviate this difficulty certain changes in structure have become necessary such as the provision of a rotatable disc mounted angularly with respect to the bottom of the container. It is therefore a particular object of our invention to provide a dispensing machine which is particularly adapted to dispense popcorn.

A further object of the invention is to provide openings in the bottom member and the rotatable disc which are adapted to register with each other at certain positions of the disc.

Since it is necessary that these openings be in close contact with each other and since the rotatable disc is mounted at an angle to the horizontal, it is a further object of the invention to provide a downwardly extending hub around the opening in the disc so that there will be a continuous channel between said opening and the opening in the bottom member.

It is another object of the invention to provide certain means to urge the inclined disc toward the bottom so that the lower edge of the hub will be maintained in contact with the upper surface of the bottom, especially during the actual dispensing operation.

A still further object of our invention is to provide means to maintain a covering for the opening in the bottom when the two openings are not in register with each other.

Other objects and purposes of the invention will appear as the description proceeds.

To the accomplishment of the foregoing and related ends said invention, then, consists of the means hereinafter fully described and particularly pointed out in the claims.

The annexed drawings and following description set forth in detail certain means for carrying out our invention, said means constituting,

however, but one of various ways in which the principle of our invention may be employed.

In said annexed drawings, wherein like reference numerals refer to like parts throughout the various views:

Fig. 1 is a front perspective view of our dispensing machine.

Fig. 2 is a fragmentary vertical section through our device showing the openings of the disc and bottom member in alignment with each other.

Fig. 3 is an under plan view of the device.

Fig. 4 is an inverted perspective view of the inclined rotatable disc.

Fig. 5 is a vertical section through a modified form of the invention, and

Fig. 6 is a vertical section taken substantially on the plane of line 6—6 of Fig. 5.

Referring now more particularly to the drawings, the device is made up generally of a container 1 and a bottom member 2 which have located therebetween a comparatively short cylindrical member 3. It may be here noted that in view of the difficulties encountered in drawing out a bottom member, the sides of which would extend upwardly a very great distance, the short cylindrical member 3 has been interposed between the bottom and main portion of the container and its lower edge is inserted within the edges of the bottom member and secured thereto such as by welding or any other desired means. The upper edge of the member 3 has a return bent portion 4 thereon and is adapted to have disposed thereagainst the rib 5 of the container 1, all as clearly shown in Fig. 2.

A plurality of legs 6 are secured at their upper ends to the outer surface of the bottom 2 in spaced apart relation to each other and serve as supporting means for the container. The bottom 2 has an opening 7 therein for the purpose of emitting the popcorn and has a surrounding flange 8 thereon. Within the container and adjacent the bottom is a rotatable disc 9 which is inclined at an angle with respect to the horizontal bottom 2. This disc also has an opening 10 therein of the same size and shape as the opening in the bottom, and extending downwardly from said opening is a hub or flange 11. In one position of the rotatable disc 9 the opening 10 is adapted to register with the opening 7 in the bottom member so that any popcorn within the container will be free to drop through the respective openings into a receptacle placed beneath said openings.

An arcuate plate 12 partially surrounds the opening 10 and the hub 11 to form the flange 13,

the remainder of which extends outwardly from said hub and is adapted to completely cover the opening 7 when the two openings 7 and 10 are out of alinement with each other as clearly shown in Fig. 3. Since the hub 11 extends downwardly and terminates in the horizontal plane of the upper surface of the bottom 2, and the arcuate plate 12 is in the same plane as the bottom edge of the hub, the plate 12 will also be in close contact at all times with the upper surface of the bottom 2. Since the plate 12 is secured to the hub 11 formed integral with the disc 9 it will move therewith as said disc is rotated so that when the two openings 7 and 10 are in alinement with each other the plate 12 will have been moved to one side, whereas, when the disc 9 is rotated to move the opening 10 out of alinement or register with the opening 7 the arcuate plate 12 will cover the opening 7, thus preventing any of the contents of the container from being removed therefrom.

The arcuate plate 12 has a curved supporting member 13 extending between itself and the disc 9 and a smaller member 14 extending therebetween each for the purpose of supporting said plate 12 and holding it in place. Also as an aid to support the disc 9 in an inclined position the supporting member 15 is placed thereon, the bottom edge 16 of which is adapted to slide over the upper surface of the bottom 2.

Extending vertically downwardly from the center of the rotatable disc 9 is a hollow member 17 which has a flange 18 thereon and at its lower end is provided with diametrically opposed openings 19 the purpose of which will be hereinafter more fully described. The bottom 2 also has a central opening therein through which the hollow member 17 is adapted to extend. Extending upwardly from the bottom member and immediately surrounding said central opening is the shoulder member 20 on which the flange 18 is adapted to rest.

A handle member 21 is provided, which is preferably made of a spring material, and which has its inner end extending through the diametrically opposed openings 19 and a cotter pin 22 is utilized to secure the handle in place. The outer end of the handle member extends beyond the edge of the container and is formed into a loop as at 23. It will therefore be seen upon moving the handle member laterally, its connection with the vertical member 17 will cause a rotation of the disc 9. Guide means are secured to the outer side of the bottom 2 as shown in Fig. 1 and consist of a lower horizontal member 24 which is curved upwardly at one end as at 25, and an upper horizontal member 26, and the handle member 21 extends between these upper and lower horizontal members. The upwardly curved portion 25 acts as a stop for the handle 21 in one direction and one of the legs 6 to which one end of the members 24 and 26 is secured acts as a stop to limit the movement of the handle in the opposite direction.

Inasmuch as it is preferable to maintain the hub 11 in contact with the edge of the opening 7 to provide a continuous channel for the emission of the material within the container, it is necessary to provide some means to urge the disc 9 toward the bottom member 2. We have been able to effect this result in a number of ways. One is by the provision of a compression spring 27 interposed between the inner end of the handle 21 and the bottom member 2 and surrounding the vertical member 17. Since the handle

is connected to the member 17, which member is in turn permanently secured to the disc 9, the downward force of the spring 27 will exert a downward pressure of the disc 9 to thereby maintain a contact between the flange 13 of the hub 11 and the upper surface of the bottom 2.

Another means which we provide to aid the spring 27 in effecting this result is the manner of positioning the handle 21. Since it is made of a spring material preferably and its inner end is secured to the vertical member 17, its outer end is forced downwardly in order that it may pass between the horizontal guide members 24 and 26 so that a slight curve in the handle will result as clearly shown in Fig. 2. In this position of the handle, the outer end thereof will tend to be raised upwardly, but since its upward movement is limited by the upper cross bar 26, there will be a tendency for its inner end to be moved downwardly. Here again it will be seen that through the connection of the inner end of the handle to the vertical member 17 and the connection of the vertical member to the disc 9, any tendency for the inner end of the handle 21 to move downwardly will also transmit this tendency to the disc 9. We therefore have not only the compression spring 27 but also the handle member 21 cooperating to urge the disc 9 downwardly so that the flange 13 and the arcuate plate 12 will be in constant contact with the upper surface of the bottom 2.

It is very desirous that the portion of the handle member which extends outwardly beyond the edge of the container be in substantial alinement with the center of the opening 10. It is also necessary, of course, that the inner end of the handle be in alinement with the center of the opening 10 because it passes directly through the center of the disc 9. Furthermore, if the handle were to extend directly across the opening 10 it would interfere with the dispensing of the popcorn in view of its comparatively large size. To obviate this difficulty we have preferred to extend the handle member 21 at approximately its center, outwardly in the form of a substantial semi-circle as at 28 in Fig. 3.

In the modification of the device shown in Figs. 5 and 6, this represents a construction which is much more economical to manufacture, but operates in substantially the same manner. In Fig. 5 the flange 8 has been omitted and the handle member 21a is situated in close proximity to the bottom 2 and substantially parallel therewith. The handle terminates at its outer end in the form of a circle 23a which is very similar to the end 23 more clearly shown in Fig. 3. Near its outer end the handle 21a abuts against the bottom of the container at its upper side and only a single cross-piece 24a is utilized. It is also to be noted that this particular construction omits the spring 27 and has in its place a plate or annular flange 51 and the slight bend in the handle member 21a may aid in maintaining the hub 11 in close contact with the bottom 2. In this particular form we have also desired to extend the flange 13 entirely around the arcuate disk 12 so that its section in Fig. 5 is denoted by the numeral 13a.

It will be obvious that it is much more important that the hub 11 be in close contact with the bottom 2 when the openings are in alinement and during the dispensing operation and for this reason an angle member 51 is secured to the side of the container tilted at an angle to the vertical equivalent to the angle at which the in-

clined disk 9 is disposed with respect to the horizontal so that the arm 52 of angle 51 is disposed at the same angle to the horizontal as the inclined disc 9. This angle member is so situated 5 that as the disc is rotated to bring the openings into alignment, the arm 52 contacts the disc 9 and acts not only as a stop means but also has a wedging action which tends to force the disc 9 downwardly in this position so that no space is allowed to remain between the bottom 2 and the 10 edge of the hub 11. The portion of the disc 9 which is contacted by the stop means is flexible in a direction parallel with its axis of rotation.

The operation of the device is explained as 15 follows:

The device as shown in Figs. 1 and 3 show the respective openings 7 and 10 out of register and in this position the arcuate plate 12 covers 20 entirely the opening 7. When the contents of the container are to be dispensed, the handle 21 is moved toward the left as viewed in Fig. 1 which will register the openings 10 and 7 and allow the contents of the container to drop through the respective openings and the channel 25 formed by the hub 11 and the flange 8. When a sufficient amount has been removed, the handle will be returned to its original position as shown in Fig. 3 wherein the opening 7 is completely covered by the bottom plate 12.

30 It is to be noted that the inclined disc 9 actually serves two purposes. The first is that it prevents the popcorn from bridging across the opening 10, which has been proven to happen by the use of a horizontal rotating disc; and 35 the second is that it enables all of the contents to be removed therefrom, thus obviating any necessity for tilting the container in its entirety in order to remove the last few pieces. Although this in itself would not present a very great difficulty, the present construction enables the container to be suspended on a wall, which would prevent its being tilted, but still permit the removal of all of the material from the container.

From the above explanation it will be seen 45 that we have constructed a dispensing machine which is particularly well adapted to dispense popcorn despite its peculiar characteristics, and at the same time, equally useful for dispensing other material. The device is easily operable 50 and economically manufactured and serves admirably the purpose for which it is intended.

Other modes of applying the principle of our invention may be used instead of the one here 55 explained, change being made as regards the mechanism herein disclosed provided, however, that the means stated by any of the following claims or the equivalent of such stated means be employed.

We, therefore, particularly point out and distinctly claim, as our invention:

1. A dispensing machine of the class described comprising, a container, a bottom secured thereto having an opening therein, a disk within said container mounted angularly with respect to said bottom for rotative movement, an opening in said disk adapted to register with the opening in said bottom, and means for rotating said disk.

2. A dispensing machine of the class described comprising, a container, a bottom secured thereto having an opening therein, a disk within said container mounted angularly with respect to said bottom for rotative movement, an opening in said disk adapted to register with the opening in said bottom in one position of said disk, means to cover the opening in the bottom when the respective

openings are not in register, and means for rotating said disk.

3. The combination of elements defined in claim 2, combined with a hub around the opening in said disk, said means to cover the opening in said bottom including an arcuate plate extending horizontally from said hub and movable with said disk. 5

4. A dispensing machine of the class described comprising, a container, a bottom secured thereto having an opening therein, a disk within said container mounted angularly with respect to said bottom for rotative movement, an opening in said disk having a hub extending downwardly therefrom adapted to register with the opening in said bottom, a handle for rotating said disk, and means connecting said handle and said disk whereby the lower edge of said hub is pressed firmly against the upper surface of said bottom. 10

5. A dispensing machine of the class described comprising, a container, a bottom secured thereto having an opening therein, a disk within said container mounted angularly with respect to said bottom for rotative movement, an opening in said disk adapted to register with the opening 15 in said bottom, a handle for rotating said disk, and means between said handle and said disk for urging said disk toward said bottom. 20

6. A dispensing machine comprising, a container, a bottom secured thereto having an opening therein, a disk mounted angularly with respect to said bottom for rotative movement, an opening in said disk adapted to register with the opening in said bottom, another opening in the center of said bottom, a vertical member extending through said central opening having its upper end secured to said disk, a flange extending around said vertical member adapted to contact the upper surface of said bottom, a handle having one end extending outwardly beyond the edge of said container and the other end secured to the lower end of said vertical member for rotating said disk, and spring means between said handle and said bottom to urge said disk toward said bottom. 30

7. The combination of elements defined in claim 6, combined with horizontal guide means for said handle, said handle being formed of spring material and positioned with respect to said guide means and said vertical member to urge said vertical member downwardly, whereby said handle aids said spring means in urging said disk toward said bottom. 45

8. A dispensing machine comprising, a container, a bottom secured thereto having an opening therein, a disk mounted angularly with respect to said bottom for rotative movement, an opening in said disk adapted to register with the opening in said bottom, a hub surrounding said last named opening and extending downwardly therefrom, an arcuate plate integral with said hub and extending horizontally therefrom and movable therewith to automatically cover the opening in said bottom when said openings are not in register, and means to rotate said disk. 55

9. The combination of elements defined in claim 8, combined with means cooperatively associated with said last named means to urge said disk toward said bottom, whereby said hub and plate will be continuously pressed against the upper surface of said bottom. 65

10. A dispensing machine comprising, a container, a bottom secured thereto having an opening therein, a disk mounted angularly with respect to said bottom for rotative movement, an opening in said disk having a hub extending therefrom 70

adapted to register with the opening in said bottom, a central opening in said bottom, a vertical member extending downwardly through said central opening and having its upper end secured to said disk, a shoulder on the upper surface of said bottom surrounding said central opening, a flange on said vertical member adapted to contact the upper side of said shoulder, a handle having one end extending beyond the edge of said container and the other end secured to said vertical member, and spring means located between said handle and said bottom, whereby said handle and spring means urge said disk downwardly to maintain the lower edges of said hub in contact with said bottom.

11. The combination of elements defined in claim 10, and an arcuate plate forming a flange about the lower edge of said hub and extending laterally from one side thereof to cover the opening in the bottom when the respective openings in the bottom and disc are not in register.

12. A dispensing machine comprising, a container, a bottom secured thereto having an open-

ing thereon, an inclined disk mounted within said container for rotative movement, an opening in said disc adapted to register with the opening in said bottom, means for rotating said disc, and means mounted on the inside of said container adapted to contact said disc after it has been rotated through a predetermined angle to thereby prevent said disc from being further rotated and at the same time to force said disc downwardly by means of a wedging action.

13. The combination of elements defined in claim 12 wherein said last named means includes an angle having one of its arms extending therefrom immediately above said inclined disc and disposed at an angle to the horizontal equivalent to the angle at which said disc is disposed to the horizontal.

14. The combination of elements defined in claim 12 in which the portion of said disc which is contacted by said means is flexible in a direction parallel with its axis of rotation.
